CLAIM

The ornamental design for an electric scooter, as shown and described.

DESCRIPTION

FIG. 1 is a front, top and left side perspective view of an electric scooter, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken line showing of the electric scooter is for the purpose of illustrating portions of the article that forms no part of the claimed design.

The dot-dash boundary line demarcates the boundary of the claimed area.
